UNITED STATES PATENT OFFICE

148,787

DESIGN FOR A GAS VALVE

James M. Haldane, Palos Heights, Ill., assignor to
Harry W. Anderson, doing business as Brass
Products Co., Chicago, Ill.

Application January 17, 1946, Serial No. 125,673

Term of patent 14 years

(Cl. D78—1)

To all whom it may concern:

Be it known that I, James M. Haldane, a citizen of the United States, residing at Palos Heights, in the county of Cook and State of Illinois, have invented a new, original, and ornamental Design for Gas Valves, of which the following is a specification, reference being had to the accompanying drawing, forming part thereof; wherein

Figure 1 is a view in perspective of a gas valve showing my new design;

Fig. 2 is a front elevation; and

Fig. 3 is a side elevation thereof.

I claim:

The ornamental design for a gas valve, as shown.

JAMES M. HALDANE.
